UNITED STATES PATENT OFFICE.

CHARLES BUTTERFIELD, OF MIDDLETOWN, OHIO, ASSIGNOR TO THE INTERSTATE FOLDING BOX COMPANY, OF MIDDLETOWN, OHIO.

FEEDING MECHANISM FOR PAPER MACHINES.

Application filed March 23, 1922. Serial No. 546,046.

To all whom it may concern:

Be it known that I, CHARLES BUTTERFIELD, a citizen of the United States, residing in Middletown, in the county of Butler and 5 State of Ohio, have invented certain new and useful Improvements in Feeding Mechanism for Paper Machines or the like, of which the following is a specification, reference being had therein to the accompanying 10 drawings.

This invention relates to paper sheet feeding mechanism, having particular reference to a feeding mechanism adapted to be used as a unit or an attachment in connection with an automatic apparatus for making paper products, as folding boxes, and the like, from paper sheets or blanks of required size and shapes, in the making of which it is essential to the automatic 15 requirements of the apparatus that delivery of the individual sheets be timed or synchronized with other units of the mechanism.

The principle of my invention is also applicable to paper sheet handling machinery 20 generally, as printing presses, paper sheet folding machines of various kinds, paper embossing machines, etc., in which it is essential, or desirable to have the delivery of the individual sheets by the feeding mechanism synchronized with other mechanisms 25 of the apparatus.

A feature of the present invention is to provide for adjustments of the feeder mechanism for various timing of the sheet delivery action and for variable sizes of sheets 30 of paper, and otherwise to adapt the feeding mechanism as a whole to the conditions of operation and of the paper stock to effect control and regulate production of the automatic paper handling apparatus.

For the purposes of illustration, the improved feeding mechanism is shown in a preferred construction in the accompanying drawings, and is claimed specifically as to 45 the form of construction illustrated, and more broadly as to the principles of the invention, in the appended claims.

In the drawings:

Fig. 1 is a side elevation of the feeding 50 mechanism;

Fig. 2 is a plan view;

Fig. 3 is a detail view of the step-by-step pick-up mechanism, and

Fig. 4 is a detail view of the automatic

stop and aligning mechanism for the paper 55 blanks.

As illustrated in the drawings, the feeding mechanism is shown as applied to the first unit of rollers —A and —B of an automatic paper folding box making apparatus,—the 60 base frame —C also being an extension of the main frame of the machine as a whole, and serving, as here shown, to support the frame —1 of the feeder mechanism. The feeding mechanism consists of an inclined 65 table —2 upon which the paper sheets are adapted to be stacked; pick-up rollers —3 and —4 automatically remove the paper sheets singly from table —2 to intermediate rollers —5 and —6, which are operatively 70 connected one to the other by equal spur gears —5^a and —6^a; the sheets being then moved by a series of carrier belts —7 to delivery rollers —8 and —9, and thence to the first unit of folding rollers —A and —B. 75

Intermediate the feed table —2 and pick-up rollers —3 and —4 is a series of inclined guides —10,—the guides being adjustable as to the angle of their inclination by a corresponding series of hand tension devices 80 —11,—thus to cause the free end of guides —10 to engage yieldingly with the peripheries of rollers —3,—the guide mechanisms being supported on upwardly extended brackets —12 fastened to a transverse shaft 85 —13 supported in the opposite frames —1. The angle of table —2 is regulated by means of a latch mechanism —2^a and —2^b. Rollers —3 and —4 are preferably rubber-tired, or otherwise provided with resilient peripheral surfaces,—thus to cause effective pick-up action of the paper sheets from table —2,—this feature of the rollers taken together with the inclination of the table and angular guides —10 being well known common practice. 95

Carrier belts —7 in their upper course of travel traverse a series of rollers —14, the ends of the rollers being supported in the opposite frames —1,—and a belt tightener 100 —15 being applied to each of the belts in its lower course of travel to maintain the belts at proper tension,—the belt tighteners being pivoted on a shaft —16 supported in opposite frames —1. A series of longitudinal 105 guides —17, supported on transverse rods —18, are arranged above and parallel with belts —7 to hold the paper sheets in con-

tact with the belts as the same are carried thereby to delivery rollers —8 and —9,— rods —18 being supported in brackets —19 extended upwardly from frames —1, and the guides being adjustable laterally by means of slip bearings —20 to adapt the spacing of the same to paper sheets of variable widths.

An intermittent, step-by-step movement 10 is transmitted to pick-up roller —3 by means of an actuating mechanism comprising a pitman —21 connected at one end, as here shown, to the shaft of roller —A by means of a slotted arm —22,—the pitman 15 connection being adjustable radially of the arm, as indicated at —23, to regulate the length of the stroke. The opposite end of the pitman is connected to one end of a rocker arm —24 pivoted in a bearing bracket —25 extended upwardly from frame —1,—a ratchet pawl —26, cooperating with a ratchet gear —27, being secured to the opposite end of arm —24,—the ratchet gear being in turn secured to a spur gear —28 20 which meshes with a gear —29 secured to the end of a shaft —30 to which pick-up rollers —3 are attached,—the lower pick-up rollers being attached to a shaft —31. Thus the upper pick-up rollers are driven 25 positively by the pitman connection in a step-by-step movement, synchronized with the movement of adjustment of the pitman connection —23,—the lower pick-up rollers —4 being driven by frictional engagement 30 with the upper rollers —3.

Roller units —A and —B are in operative relation one with the other by means of equal gears —a and —b,—the lower gear —b acting as a driver for the carrier belts 40 —7 and delivery rollers —8 and —9,—the driving movement being transmitted to belt roller —32 through an intermediate gear train —33 —34 —35 and —36,—gear —36 being attached to belt roller —32; and to 45 rollers —8 and —9 through gear trains —33 —34 —37 and —38,—gear —37 being attached to roller —8 and gear —38 to roller —9,—the gear ratios of the carrier belt driving mechanism being such as will effect 50 the proper advance of the sheets of paper to the delivery end of the feeder mechanism, and of the driving mechanism for rollers —8 and —9 to effect proper timing of the sheets as delivered to the movement 55 of rollers —A and —B.

As is best shown in detail Fig. 4, the sheet delivery action of rollers —8 and —9 is further controlled relative to the movement of rollers —A and —B by a mechanism 60 comprising cams —37^a attached to the opposite ends of shaft —38^a upon which rollers —A are supported,—each cam comprising two adjacent cam discs arranged face to face in contact one with the other, and having equal peripheral depressions 65

—39,—the discs being adjustable rotatably relative to each other to vary the length of the coinciding portions of depressions —39 of the opposite discs. Roller —8 is operatively connected to cams —37^a by means of opposite arms —40 having extension arms —41 secured thereto by means of clamp bearings —42 in which the opposite ends of roller —8 are supported,—thus causing arms —40 and —41 to act as one 70 on pivot centers —43 under tension of springs —44, and roller —8 to be lifted sufficiently to free the paper between rollers —8 and —9 as cam rollers —45 at the opposite ends of levers —40 are moved by the action of springs —44 into the cam depressions —39,—it being understood from the arrangement illustrated, that roller —8 will be held in positive feeding relation with roller —9 by the cam discs —37 except during the interval at each full rotation of the cams that cam rollers —45 are in engagement with cam depressions —39.

A transverse paper guide —46 is arranged adjacent rollers —8 and —9 and a series of automatic stops —47, operable through apertures —48 in guide —46, and attached to a rock shaft —49, cooperate with the guide to stop the movement of the paper sheet between rollers —8 and —9 when roller —8 is in raised position and also to align the sheet as it is moved against the stops,—movement of the stops being effected and regulated with the rollers —A and —B by an adjustable connection between arms —40 and shaft —49 consisting of arms —50 attached to the shaft and adjustable links, or shafts —51, connecting arms —50 to downwardly extended arms —52 of arms —40.

From the described arrangement, it will be observed that stops —47 will be in raised position to engage the paper sheet when it is between rollers —8 and —9, during the interval roller —8 is in raised position,—the sheet being then free on carrier belts —7, and that the paper sheet will thus be brought to position, properly aligned, and timed to the movement of rollers —A and —B, and that positive delivery of the sheet will be made upon return of roller —8 to feeding relation with roller —9.

Having described my invention, I claim:

1. A paper feeding mechanism, including in combination with a main machine, a longitudinal frame connecting at one end with said main machine, an inclined table arranged at the opposite end of said frame to receive paper sheets in quantities, pick-up mechanism operable intermittently through connections with said main machine and adapted to deliver the paper sheets singly from said table, paper feeding mechanism arranged at the opposite ends of said frame coacting with a paper carrier operable be-

- between said opposite paper feeding mechanisms, means for interrupting the effective operation of the feeding mechanism adjacent said main machine, and other means 5 for stopping the paper on the paper carrier during said period of interruption, whereby the paper is delivered from said table in single sheets to said main machine.
2. A paper feeding mechanism, including 10 in combination with a main machine, a longitudinal frame connecting at one end with said main machine, an inclined table arranged at the opposite end of said frame to receive paper sheets in quantities, pick-up 15 mechanism operable intermittently through connections with said main machine and adapted to deliver the paper sheets singly from said table, paper feeding mechanism arranged at the opposite ends of said frame 20 coacting with a paper carrier operable between said opposite paper feeding mechanisms, means timed with the operation of the main machine for interrupting the effective operation of the feeding mechanism adjacent 25 said main machine, whereby the paper is delivered from said table in single sheets to said main machine.
3. A paper sheet feeding mechanism, including in combination with a main machine, a support for the paper, pick-up mechanism cooperating with said support to deliver the paper sheets singly therefrom, sheet delivery mechanism cooperating with said pick-up mechanism comprising a sheet carrier, separable rollers and aligning stops for the paper sheets as the same are delivered between said rollers, said rollers and stops being operable synchronously with the main machine to present the paper sheets thereto aligned and timed to the movement thereof.
4. A paper sheet feeding mechanism, including in combination with a main machine, a support for the paper, pick-up mechanism cooperating with said support to deliver the paper sheets singly therefrom, sheet delivery mechanism cooperating with said support to prevent movement of the paper sheets between the rollers during an interval of said inoperative relation, operation of said rollers and stops being synchronized with the main machine to present the paper sheets thereto timed to the movement thereof.
5. A paper sheet feeding mechanism, including in combination with a support for the paper, step-by-step pick-up mechanism 60 cooperating with said support to deliver the paper sheets singly therefrom, intermittently-operable sheet delivery mechanism spaced from said pick-up mechanism, and constantly-operable sheet carrier mechanism 65 operable between said pick-up and delivery mechanisms, all of said mechanisms being coordinated operatively one with the other, and mechanism coacting with said mechanisms and synchronized operatively therewith to receive the paper sheets therefrom.
6. A paper sheet feeding mechanism, including in combination with a support for the paper, step-by-step pick-up mechanism 70 cooperating with said support to deliver the paper sheets singly therefrom, intermittently-operable sheet delivery mechanism spaced from said pick-up mechanism, and constantly-operable sheet carrier mechanism 75 operable between said pick-up and delivery mechanisms, all of said mechanisms being coordinated operatively one with the other, and mechanisms comprising driving connections for the pick-up mechanism, and other driving connections for said carrier and delivery mechanisms, and having operative movement synchronized with the movement and delivery of the paper sheets thereto by said coordinated mechanisms.

In testimony whereof, I affix my signature.

CHARLES BUTTERFIELD.
